P. E. BRENEMAN

TOP CONSTRUCTION

Filed March 17, 1926

UNITED STATES PATENT OFFICE.

PAUL E. BRENEMAN, OF DETROIT, MICHIGAN, ASSIGNOR TO THE STUDEBAKER CORPORATION, OF SOUTH BEND, INDIANA, A CORPORATION OF NEW JERSEY.

TOP CONSTRUCTION.

Application filed March 17, 1926. Serial No. 95,314.

This invention relates to vehicle tops of the permanent type, and particularly to side rail constructions therefor, the main object being to provide such a construction of new and novel design, which will be light in weight, easy to assemble and economical to manufacture.

Another object is to provide a permanent type vehicle top with a side rail constructed of a sheet metal base and a sheet metal contoured member, to both of which is secured a wooden tacking member.

Another object is to provide a vehicle top side rail comprising a suitably reinforced sheet metal base and a contoured member rolled together along their outer edges and secured along their inner edges to a common tacking strip.

These being among the objects of the present invention, the same consists of certain features of construction and combinations of parts to be hereinafter described with reference to the accompanying drawing, and then claimed, having the above and other objects in view.

In the accompanying drawing which illustrates a suitable embodiment of the present invention and in which like numerals refer to like parts throughout the several views:

Figure 1 is a partial perspective view of a vehicle body having a top incorporating the features of the present invention, assembled thereon.

Figure 2 is an enlarged sectional view taken through one of the side rails and longitudinally through one of the cross-struts.

Figure 3 is an enlarged perspective view taken transversely through one of the side rails at a point adjacent a cross-strut.

Figure 4 is a perspective sectional view of a modification of the side rail shown in Figures 2 and 3.

Figure 5 is a sectional view taken transversely of the modified form of side rail shown in Figure 4, and longitudinally through one of the cross-struts, showing the connection therebetween.

Figure 6 is a cross sectional view of one

of the cross-struts illustrated in the several preceding views.

The top, in general, comprises those elements which are common to most of the conventional types, namely, side rails 10, a front cross piece 11, a rear cross piece 12 and cross-struts 13 spanning the space between the side rails 10. These elements are first assembled to complete the top structure and then attached to the vehicle body by suitable brackets and the like.

It will be noted that each side rail 10 is supported on the body pillars 14 and rear quarter panel 15 by a longitudinal member which will be designated in the following description as the base member. Referring now to Figures 2 and 3 in particular, this base member is stamped from a single sheet of metal to provide a U-shaped door stop portion 17, one leg 18 of which extends vertically upwards and flanges inwardly at substantially right angles thereto to provide the flange 19, and the other leg 20 of which extends upwardly a slight distance and flanges outwardly to provide the substantially horizontal portion 21 which terminates in an upwardly extending marginal flange or leg 22.

The cross-struts 13 previously mentioned extend at regularly spaced intervals from one side rail 10 to the other and may be trough shaped in form, each being stamped in one operation from a single sheet of metal, rendering a very light, efficient and economical construction. The ends of each cross-strut 13 are preferably welded to the top face of the flange 19.

Although not essential, it is desirable to provide reinforcing means to provide additional strength to the base member substantially at the point where the cross-struts 13 are secured thereto. This may be obtained by providing suitable reinforcing members such as the Z-shaped reinforcing bars 23 made of strap iron, but may be of any other practical shape or material. The Z-shaped bar 23 is more adapted to the present construction as one leg may be conveniently secured to the horizontal portion 21 and the other leg thereof may be conveni-

ently secured (preferably welded), to the horizontal flange 19 and to the bottom of the trough portion of the cross-strut 13.

Butting against the ends of the cross-struts 13 or in close proximity thereto is a longitudinal wooden tacking member 24, portions being cut away on the under surface thereof to allow the same to fit over and around the reinforcing bars 23 and to lie flatly on the flange 19. Nails or screws such as 25 passing through the flange 19 may be provided to securely hold the tacking member 24 in a rigidly fixed position.

In order to impart a finished appearance to the rail as thus far described, and to give it added strength, a contoured member 26, also formed of sheet metal, is provided to conceal these parts and to lend shape and strength to the side rail 10. For the most part, it has a convex outer surface 27 formed with a trough-shaped outer edge comprising a flat portion 28 and an upwardly extending flange 29, the inner edge 30 being suitably secured by nails 31 or the like to the upper surface of the tacking strip 24 and the flange 29 abutting against the marginal flange 22 of the horizontal portion 21. The upper edge of this marginal flange 22 is bent back on itself to clamp the flange 29 therebetween, thereby holding the base member and contoured member 26 firmly secured together along their respective outer edges and forming the trough 32.

Vehicle tops used previous to this time were usually provided with a drip trough in combination with a suitable molding to catch the water and rain which fell from the top and convey it to the rear end thereof to discharge it. The trough 32 eliminates the need of providing this additional trough and molding, thereby making it a very economical construction.

Any desirable top material such as 33 may be provided to cover the top and may be secured thereto by tacking it to the tacking strip 24, a molding 34 being nailed thereto to conceal the edge of the top material and to conceal the edge 30 of the contoured member 26.

In Figures 4 and 5 a slight modification of the side rail 10 just described is illustrated. This side rail comprises essentially the same elements, namely, a contoured member 40 of substantially the same shape and construction, a base, a tacking strip 42, reinforcing members 43 and cross-struts 44, all of which are assembled in a slightly different manner.

The base is shaped from sheet metal to provide a pair of downwardly converging surfaces 45 and 46 which meet in a longitudinal door stop projection 47, similar to the door stop projection 17 of Figure 3. The inner edge of the surface 46 is turned upwardly to form the face 48 and then turned

inwardly to form the inner marginal flange 49. The outer edge of the surface 45 is bent upwardly to provide the marginal flange 50 which is bent back on itself over the marginal flange 51 of the contoured member 40 thereby to secure it to the same and to provide the trough 52 which functions the same as the trough 32 of the previously described side rail 10.

The tacking member is secured by bolts 75 such as 53 to the face 48 substantially flush with the flange 49 and the flanges 54 of the cross-strut 44 are preferably welded to the under surface of the flange 49 as shown in Figure 5. The reinforcing members 43 are 80 suitably shaped to be secured to the sloping surface 45, to partially support the tacking member 42 and to be secured to the under surface of the bottom of the cross-struts 44. Although not shown, suitable top covering and a molding are provided in a 85 way similar to that illustrated in Figures 2 and 3.

Certain advantages of the present invention can be seen over the type of top side rail heretofore used. It can be seen that the side rails as illustrated and described herein may be easily and economically produced, especially in large quantities, that they are simple in construction and light in weight, and that they can be assembled very economically and easily.

Formal changes may be made in the specific embodiment of the invention described without departing from the spirit and substance of the broad invention, the scope of which is commensurate with the appended claims.

What I claim is:

1. In a vehicle top of the permanent type, side rails comprising contoured members and sheet metal base members, each base member having a vertical portion and an inwardly extending flange formed at the upper edge of said portion, Z-shaped reinforcing members extending transversely of said base member and inwardly therefrom secured to the upper face thereof, channel-shaped cross-struts holding said side rails in spaced relationship, the bottom face of the base of said cross-struts being secured to the upper face of said base member and the inner face secured to said reinforcing member, and a tacking strip secured adjacent the free end of each of said base members and to the free end of each of said contoured members.

2. In a vehicle top of the permanent type, side rails comprising contoured members and sheet metal base members secured together at their outer edges, each base member having a horizontal portion, a vertical portion extending upwardly from said horizontal portion, and a second horizontal portion extending inwardly from the upper edge of said vertical portion, cross-struts each hav-

ing the base thereof secured to said last-named horizontal portion of said base member, Z-shaped reinforcing members extending transversely of said base member secured to said horizontal portions thereof and to said cross-struts, and a wooden tacking strip secured adjacent the free edge of

each of said base members and to the free edge of each of said contoured members, said tacking strip being of greater depth ¹⁰ than said cross-struts.

Signed by me at Detroit, Michigan,
U. S. A., this 12th day of March, 1926.

PAUL E. BRENEMAN.
